[57] **CLAIM**

The ornamental design for handheld input device computers, as shown and described.

DESCRIPTION

FIG. 1 is a perspective view of a handheld input device for computers incorporating the features of my design; FIG. 2 is a top plan view of the handheld input device for computers;

FIG. 3 is a left side elevation view thereof, the right side being the mirror image;

FIG. 4 is a bottom plan view of the handheld input device for computers;

FIG. 5 is a front end view of the handheld input device for computers laying on its left side; and,

FIG. 6 is a rear end view of the handheld apparatus for computers laying on its left side.

The broken line drawing of the bottom portion of the input device is for illustrative purposes only and forms no part of the claimed design.

FIG. 1

FIG. 2

FIG. 3

FIG. 4

FIG. 5

FIG. 6
